UNITED STATES PATENT OFFICE.

EDGAR E. PHINNEY, OF NEW YORK, N. Y., ASSIGNOR TO MONROE CALCULATING MACHINE COMPANY, OF NEW YORK, N. Y., A CORPORATION OF NEW YORK.

CALCULATING-MACHINE.

1,396,662.

Specification of Letters Patent. Patented Nov. 8, 1921.

Application filed December 26, 1918. Serial No. 268,343.

To all whom it may concern:

Be it known that I, EDGAR E. PHINNEY, a citizen of the United States, resident of New York, in the county of New York and State of New York, have made a certain new and useful Invention in Calculating-Machines; and I declare the following to be a full, clear, and exact description of the same, such as will enable others skilled in the art to which it appertains to make and use the invention, reference being had to the accompanying drawings, and to letters or figures of reference marked thereon, which form a part of this specification.

Figure 1 is a side view of the invention with the side frame plate removed and parts broken away.

Fig. 2 is a section on the line 2—2, Fig. 1.
Fig. 3 is a section on the line 3—3, Fig. 2.

Fig. 4 is a detail perspective view of the driven disk.

Fig. 5 is a detail transverse section taken through the plane of the cross-form member.

Fig. 6 is a detail perspective view of the 25 pinion and driving disk.

Fig. 7 is a detail perspective view of the cross-form member.

Fig. 8 is a fragmentary section taken on the line 8—8, Fig. 11.

Fig. 9 is a fragmentary section taken on the line 9—9, Fig. 11.

Fig. 10 is a detail face view of the digital keys of a bank.

Fig. 11 is a section taken on the line 35 11—11, Fig. 8.

The invention has relation to calculating machines, of the type shown in the reissue patent to Baldwin No. 13,841, dated December 8, 1914, as modified in the patent to 40 Phinney, No. 1,253,879, dated January 15, 1918.

The object of the invention is to provide a machine having all of the advantages stated in the said patent to Phinney, where- 45 in the selecting or differential actuating wheels and the driving elements or dogs of the carry mechanism may be rotated continuously through one or more cycles of operation, and having further a driving 50 train for these parts which will transmit motion thereto from the operating handle at a constant speed ratio.

The invention consists in the novel construction and combinations of parts as here- 55 inafter set forth.

In the accompanying drawings illustrating the invention, the numeral 1, designates the casing of the machine; 2 the transversely shiftable carriage whereon the register wheels 13 are mounted; 3 the operating handle; 4 the shaft upon which the selecting or differential actuating wheels 5 are mounted; 12 the gears intermediate of the selecting and register wheels; 73 the shaft upon which the carry mechanism is mounted bearing the 60 radial arms *m*, and the dogs *j*; and 74, 75, and 76 a train of gear wheels establishing a driving connection between the shaft 73 and the operating handle.

The selecting wheels 5 consist of gears 70 having teeth of graded extent, and are shiftable laterally upon their shaft 4 to bring a selected number of teeth in position to register with the respective intermediate gears 12. Each selecting wheel 5 has a bank of 75 digital keys 18 associated therewith, the lower cam heads 25 of the keys acting through rock bars 19 to impart the appropriate degree of lateral movement to the selecting wheels 5.

The shaft 4 and the selecting wheels thereon are adapted to be vibrated to and fro into and out of driving engagement with the intermediate gears by means shown in the said patent to Phinney and consisting of 85 levers 15, wherein the shaft 4 is journaled, said levers being fulcrumed at 16 to the side plates of the frame or casing and having diverging or branched arms 17 carrying anti-friction rollers the latter bearing upon 90 the peripheral surfaces of rotary cams 19, fast to the shaft 73.

In the rotation of the cams, the levers 15 will be first rocked to one side to move the shaft 4 and the selecting wheels bodily toward the intermediate gears to bring said wheels from normal or neutral position into full mesh with said gears, and after the rotation of the selecting wheels in the registering operation, said levers will be 100 reversely rocked to move said shaft and the selecting wheels reversely to and past normal position to bring said wheels entirely out of mesh with the intermediate gears where they will remain during the operation of the carrying mechanism. In the completion of the operation the levers will be rocked to restore the selecting wheels to normal position.

Were a planetary or chain gear connec- 110

tion employed between the shaft 4 and the main driving train, in the bodily movement of said shaft and of the selecting wheels thereon to bring said wheels into full mesh 5 with the intermediate gears (this operation being preliminary to the performance of a problem) the selecting wheels would be always rotated, irrespective of the movement of the driving gear, owing to the engagement of the driven with the driving member of said connection.

In the movement of the gears in one direction for the performance of addition, the rotation of the selecting wheels referred to 15 will be subtracted from the rotation of said wheels brought about by the driving gear movement alone to cause a retardation of the rotation of the selecting wheels, and per contra in the movement of the gears in 20 the opposite direction as in performing subtraction, the extra rotation of the selecting wheels referred to will be added to the rotation thereof by the driving gear to cause an acceleration of the rotation of the selecting 25 wheels. This acceleration and retardation of these wheels will result in an objectionable variable resistance to the movement of the operating shaft or handle and is eliminated by this invention now to be described.

A pinion 21 in mesh with the gear 75 of the driving train is mounted upon a stud shaft 20 of the framing and is provided with a driving connection with the shaft 4 30 of the selecting wheels through the following medium:

A driving disk 22, fast to the stud shaft is provided with diametric lateral recesses 23 and 24, crossing at right angles, the recess 23 being of greater breadth than the recess 24, and as a result of the recesses, the disk is provided with four sector-form lateral projections 25, spaced apart by the recesses. A driven disk 26 is fast to the adjacent end of the shaft 4, and is similarly provided with diametric recesses 27 and 28, crossing at right angles and with four sector-form lateral projections 29, spaced apart by the recesses, the wide and narrow 40 recesses of one disk being located respectively opposite the narrow and wide recesses of the other disk. Between the driving and driven disks is a floating cross-form connecting member 30, having four 45 radial arms 31, of the same width respectively as that of the narrow recesses of the disks, two opposite arms of said member having close sliding engagement with the narrow recess of one disk and laterally loose engagement with the wide recess of the other disk, and the other two arms of said member having laterally loose engagement with the wide recess of the first named disk, and close sliding engagement with the narrow recess of the last named disk.

Starting from normal position, when the selecting wheels are in neutral position or only partly in mesh with the intermediate gears as stated and shown in Fig. 3, and the bodily movement of the selecting wheels 70 toward the intermediate gears into full mesh therewith taking place, and the selecting wheels being rotated to drive said gears in the performance of the problem and thereafter moved bodily reversely entirely 75 out of mesh with the gears and finally back again to neutral or normal position, and the driving disk rotating the driven disk throughout this operation, the driven disk will vibrate or move to and fro bodily with 80 the selecting wheels and the cross-form member will likewise vibrate or move to and fro, two opposite arms of said member sliding lengthwise of the narrow recess of the driven disk and moving bodily across the 85 wide recess of the driving disk, and the other two arms of said member sliding lengthwise of the narrow recess of the driving disk and moving bodily across the wide recess of the driven disk. The vibration or movement to and fro of the said member in said recesses is not however in unison with the vibration or bodily movement of the selecting wheels and driven disk toward 90 and away from the intermediate gears.

The cross-form member and the driving and driven disks therefore provide a medium whereby the stud shaft will always rotate the shaft of the selecting wheels in the vibratory bodily movement of the latter without lost motion or appreciable added friction.

It is preferred that when the selecting wheels are in full mesh with the intermediate gears, the shaft thereof shall be axially aligned with the stud shaft 20, for the reason that in this relation of the shafts, the cross-form member and the driving and driven disks will constitute a rigid driving connection between the stud shaft and the shaft of 100 the selecting wheels with no added friction whatever.

I claim:—

1. In a calculating machine, register wheels, selecting wheels adapted to rotate the register wheels, carry mechanism adapted to thereafter rotate the register wheels, an operating shaft, and means adapted to rotate the selecting wheels and the carry mechanism continuously and during the rotation of the operating shaft and for vibrating the selecting wheels into and out of driving connection with the register wheels without modification of the rate of rotation thereof.

2. In a calculating machine, register wheels, a set of selecting members adapted to rotate the register wheels, a set of carry members adapted to thereafter rotate the register wheels, an operating shaft, and

- means adapted to rotate the selecting members and the carry members continuously and during the rotation of the operating shaft and for vibrating one set of members 5 into and out of operative relation to the register wheels without modification of the rate of rotation thereof.
3. In a calculating machine, register wheels, selecting wheels adapted to rotate 10 the register wheels, carry mechanism adapted to thereafter rotate the register wheels, an operating shaft, and means adapted to rotate the selecting wheels and the carry mechanism continuously and at an even rate 15 of speed during the rotation of the operating shaft and for vibrating the selecting wheels into and out of driving connection with the register wheels and including a driving element, a member fast thereto, a member fast 20 to the shaft of the selecting wheels, and a loose connecting member.
4. In a calculating machine, register wheels, selecting wheels adapted to rotate 25 the register wheels, carry mechanism adapted to thereafter rotate the register wheels, an operating shaft, and means adapted to rotate the selecting wheels and the carry mechanism continuously and at an even rate 30 of speed during the rotation of the operating shaft and for vibrating the selecting wheels into and out of driving connection with the register wheels and including a driving element, a recessed member fast thereto, a recessed member fast to the shaft of the selecting 35 wheels, and a loose connecting member having arms working in the recesses of the first named members.
5. In a calculating machine, register wheels, selecting wheels, adapted to rotate 40 the register wheels, carry mechanism adapted to thereafter rotate the register wheels, an operating shaft, and means adapted to rotate the selecting wheels and the carry mechanism continuously and at an even rate 45 of speed during the rotation of the operating shaft and for vibrating the selecting wheels into and out of driving connection with the register wheels and including a driving element, a member fast thereto having diamet- 50 ric recesses of different widths, a member fast to the shaft of the selecting wheels and having also diametric recesses of different widths, and a cross-form member interposed between the recessed members and having 55 its arms working in the recesses thereof.
6. In a calculating machine, register wheels, selecting wheels, adapted to rotate 60 the register wheels, carry mechanism adapted to thereafter rotate the register wheels, an operating shaft, and means adapted to rotate the selecting wheels and the carry mechanism continuously and at an even rate of speed during the rotation 65 of the operating shaft and for vibrating the selecting wheels into and out of driving relation to the register wheels and including a train of three gears between the operating and carry shafts, a stud shaft having a gear in mesh with the center gear of said train, and a driving connection interposed between 70 the stud shaft and the selecting shaft.
7. In a calculating machine, register wheels selecting wheels adapted to rotate the register wheels, carry mechanism adapted to thereafter rotate the register wheels, an operating shaft, and means adapted to rotate the selecting wheels and the carry mechanism continuously and at an even rate of speed during the rotation of the operating shaft and for vibrating the selecting wheels into and out of driving connection with the register wheels and including a train of three gears between the operating and carry shafts, a stud shaft having a gear in mesh with the center gear of said train, a member fast to the stud shaft, a member fast 75 to the selecting shaft, and an adjustable connecting member.
8. In a calculating machine, register wheels, selecting wheels adapted to rotate 80 the register wheels, carry mechanism adapted to thereafter rotate the register wheels, an operating shaft, and means adapted to rotate the selecting wheels and the carry mechanism continuously and at an even rate 85 of speed during the rotation of the operating shaft and for vibrating the selecting wheels into and out of driving connection with the register wheels and including a train of three gears between the operating and carry shafts, a stud shaft having a gear in mesh with the center gear of said train, a member having diametric recesses fast to the stud shaft, a member having diametric recesses fast to the selecting shaft, and a 90 floating cross-form member.
9. In a calculating machine, register wheels, actuating means therefor, and means for vibrating the actuating means into and out of driving relation to the register wheels and for rotating the actuating means throughout the vibratory movement and including a driving element, a member fast thereto, a member fast to the shaft of the actuating means and a connecting member 95 adjustable by and coacting with the first named members.
10. In a calculating machine, register wheels, actuating means therefor, and means for vibrating the actuating means into and out of driving relation to the register wheels and for rotating the actuating means throughout the vibratory movement and including a driving element, a recessed member fast thereto, a recessed member fast to the shaft of the actuating means, and a connecting member having arms working in the recesses of the first named members.
11. In a calculating machine, register wheels, actuating means therefor, and means 105

for vibrating the actuating means into and out of driving relation to the register wheels and for rotating the actuating means throughout the vibratory movement and including a driving element, a member having diametric recesses of different widths fast to the driving element, a member having diametric recesses of different widths fast to the shaft of the actuating means, and a cross-form connecting member.

12. In a calculating machine, selecting mechanism including a shaft, a plurality of driving elements mounted thereon and a series of digital keys for each element, carry mechanism including a shaft and a plurality of driving elements mounted thereon, numeral wheels operable by the selecting elements and carry elements, an operating device, and means whereby movement of said device may be transmitted at a constant speed ratio to the selecting elements and to the carry elements through successive cycles of operation.

13. In a calculating machine, selecting mechanism including a shaft, a plurality of driving elements mounted thereon and a series of digital keys for each element, carry mechanism including a shaft and a plurality of driving elements mounted thereon, numeral wheels rotatable in either direction by the selecting elements and carry elements, an operating device, and means whereby movement of said device to effect forward or reverse rotation of said numeral wheels may be transmitted at a constant speed ratio to the selecting elements and to the carry elements through successive cycles of operation.

14. In a calculating machine, selecting mechanism including a shaft, a plurality of driving elements mounted thereon and a series of digital keys for each element, carry mechanism including a shaft and a plurality of driving elements mounted thereon, numeral wheels operable first by the selecting elements and thereafter by the carry elements, an operating device selectively movable in the performance of arithmetical

problems of opposite nature, and means whereby movement of said device in either selected direction may be transmitted at a constant speed ratio to the selecting elements and to the carry elements through successive cycles of operation.

15. In a calculating machine, selecting mechanism including a shaft, a plurality of driving elements mounted thereon and a series of digital keys for each element, carry mechanism including a shaft and a plurality of driving elements mounted thereon, numeral wheels operable by the selecting elements and carry elements, an operating device rotatable in either of two directions, and means whereby rotation of said device in either direction may be transmitted at a constant speed ratio to the selecting elements and to the carry elements through successive cycles of operation.

16. In a calculating machine, selecting mechanism including laterally adjustable driving elements, carry mechanism including driving elements, numeral wheels operable by the selecting elements and carry elements, an operating device, and means whereby movement of said device may be transmitted at a constant speed ratio to the selecting elements and to the carry elements through successive cycles of operation.

17. In a calculating machine, selecting mechanism including laterally adjustable gears, carry mechanism including rotary elements, numeral wheels operable by the selecting gears and carry elements, an operating device, and means whereby movement of said device may be transmitted at a constant speed ratio to the selecting gears and to the carry elements through successive cycles of operation.

In testimony whereof I affix my signature in presence of two witnesses.

EDGAR E. PHINNEY.
